ARTHUR W. POPE, JR., OF WAUKESHA, WISCONSIN, ASSIGNOR TO WAUKESHA MOTOR CO., OF WAUKESHA, WISCONSIN, A CORPORATION OF WISCONSIN

GAS ELECTRIC DRIVE CONTROL

Application filed July 21, 1926. Serial No. 123,970.

My invention relates to drive control in vehicle propulsion systems in which a current generator coupled to the vehicle internal combustion engine supplies current for driving motors usually mounted on the vehicle driving axle.

With the driving motor positively connected to the driving axle of the vehicle, the motor speed varies with the vehicle speed, and the voltage required to maintain a given power input to the motor increases as the vehicle speed increases, and in order to obtain higher voltage for offsetting the motor counter electro-motive force it is necessary to run the generator and engine faster. The faster a motor is run, the higher will be the voltage required to maintain the power input and proper propulsion of the vehicle. It is this variable load on the generator caused by the variable vehicle speed which has caused the most difficulty in the operation of gas-electric drive systems.

It is the object of my invention to overcome these difficulties by controlling the generator characteristics by a speed sensitive governor driven by the vehicle engine so that a predetermined fixed engine and generator speed will be maintained regardless of variations in the line resistance caused by change of vehicle speed.

In the drawings:

Figure 1 is a diagram of the motor driven generator governor and the generator and the variable resistance therefore actuated by the governor, and associated parts.

Figure 2 is a diagram of the throttle control valve of the engine and the engine driven governor therefor and associated parts, the manually operated throttle valve being also shown.

The engine E has the intake manifold 1 with which is connected a carburetor C having the throttle valve 2. The throttle lever 3 is connected by rod 4 with the foot lever 5.

In the intake manifold 1 is the governor throttle valve 6 controlled by the engine governor A. This governor structure may be of any well known type. As shown it comprises the bell crank weight levers 7 and 8 pivoted on the bracket 9 carried by one of the engine

shafts, in this case, the cam shaft 10. The levers at their inner ends cooperate with an abutment 11 connected with the lever 12 of the governor throttle valve as by means of a rod 13, the adjustable governor spring 14 being shown connected with the end of the lever to resist closure of the valve 6 which normally is wide open. As is well understood in the art, the engine governor automatically controls the fuel supply to the engine from the carburetor and tends to keep the engine running at a constant speed.

The engine is directly coupled to the generator G to rotate the armature 15. Extending from the generator commutator brushes or terminals 16 and 17 is the external circuit 18 in which is included a series field winding 19, the driving motors M being connected with the external circuit in series, in parallel, or in series-parallel arrangement and are positively connected to the driving axle of the vehicle to be propelled.

The characteristic or output determining elements of the generator include, besides the series field winding 19, the shunt field winding 20 and an adjustable field resistance 21. I may also provide a tickler or excitation field winding 22. The field resistance 21 is subdivided by a plurality of contacts 23 to be engaged by a contact arm 24 pivoted at 25. A manually operable setting lever 26 is pivoted at 27 and has a contact spring 28 for cooperation with a contact or terminal segment 29. One terminal of the shunt field winding 20 is connected with the generator terminal or brush 16 and the other end of the winding is connected by conductor 30 with the segment 29. A conductor 31 electrically connects the levers 26 and 24 and the outer terminal of the resistance 21 is connected by conductor 32 with the generator brush or terminal 17. By movement of the lever 24 along the resistance contacts 23 the resistance of the shunt field circuit is adjusted.

The tickler circuit includes a battery 33 in series with the tickler field 22 and the end of the circuit terminates in flexible contacts 34 and 35 which normally keep the tickler circuit open but which are located ad-

ja cent to the setting lever 26 to be brought into engagement when the lever 26 is moved toward the segment 29, being however, electrically disconnected from the levers.

5 In accordance with my invention I provide a generator governor B for operating the resistance contact lever 24 to control the resistance of the generator field circuit. This governor, like the engine governor A may be 10 of well known construction, it being shown as comprising the weight levers 36 and 37 pivoted on a frame 38 secured on the cam shaft 10 of the engine, the inner ends of the levers engaging the abutment 39 at the end 15 of a rod 40 which is connected to the resistance lever 24 a distance inside of the lever pivot point 25. Between the extension 41 of the setting lever 26 and the resistance lever 24 is connected the generator governor spring 20 42 which resists the pull of the rod 40 to move the lever 24 in resistance reducing direction. As before stated, the hand lever 26, by engaging with the segment 29 serves to close the shunt field circuit. The lever serves 25 also to adjust the tension of the spring 42, and during the normal or open position of the hand lever the spring is at maximum tension but as the lever is swung to the left the tension of the spring is reduced.

30 Before the operator propels the vehicle, he first starts the engine in the usual way and opens the engine throttle 2 wide so that the engine can come up to governed speed without load, the generator running idle. Having 35 started the engine the operator swings the setting lever 26 just far enough to make electrical contact with the segment 29. This is the low torque or low speed position and by this starting movement of the lever the shunt 40 field circuit of the generator is closed and the contacts 34 and 35 are also engaged to close the tickler's circuit. The tickler field winding excites or magnetically primes the generator and also keeps the generator from 45 losing its magnetic field at low speed when the shunt field is very weak.

When the engine is started the engine governor operates to control the intake valve 6 and the generator governor B tends to swing 50 the resistance lever 24. However, the initial movement of the setting lever 26 is insufficient to relieve the tension of the spring 42 sufficiently to allow any material movement of the resistance arm 24 by the generator 55 governor and so practically all of the resistance 21 is included in the shunt field circuit during the low torque position of the setting lever. In this low torque position the engine will be held by the generator to a speed 60 at which the engine develops its maximum power regardless of what the vehicle speed may be.

By moving the setting lever farther along the segment 29 the tension of the generator 65 governor spring 42 is reduced and the gener-

ator governor can act to swing the resistance arm 24 to reduce the resistance in the shunt field circuit. The generator torque will increase and will be maximum when all the resistance has been cut out of the shunt field 70 circuit and this increased or maximum generator torque may be applied during the lower speeds of the engine. On level road running at constant speeds it is desirable to reduce the engine speed as much as possible and this is 75 accomplished by moving the setting lever to the high torque position. For accelerating or hill climbing, when the maximum output of the engine is desired, the lever will be set in the low torque position. For each position 80 of the setting lever and corresponding tension adjustment of the spring 42, the generator governor B will automatically adjust the generator field resistance for the desired 85 operating condition, and for each position 85 of the lever there is therefore a definite fixed speed determined for the engine regardless of vehicle speed or throttle opening, that is, for any throttle opening great enough to permit this engine speed with the generator 90 control in the minimum torque position.

All that the operator needs to do is to set the lever 26 for the automatic establishment by the generator governor of the desired running condition, and then operate the foot control throttle lever 5, the operation of this throttle control lever permitting reduction in engine speed below the governed speed determined by the engine governor A. In other words, the operator sets the lever 26 95 for the practical operation of the vehicle under the existing conditions and he operates the foot throttle lever 5 to vary the speed of the engine as desired, but only up to the governed maximum speed. With the establishment of desired generator characteristics 100 he runs the vehicle faster or slower as desired. The change in engine speed automatically controls, through the generator governor B, the strength of the generator field and consequently the generator output to the vehicle motors and all this is automatically performed without depending on the personal element. As the vehicle speed 105 and that of the motors increases, and the engine increases its speed due to the increased resistance in the generator external circuit, the generator governor speed and pull will be increased and the field resistance correspondingly reduced to hold the generator 110 pressure normal.

An important feature and advantage of my invention is that the generator and engine can be brought up to speed before applying the load. This will give more rapid acceleration of the vehicle because the inertia of the generator and engine does not have to be overcome.

I have illustrated my invention, by way of example, as applied to an internal combus- 130

tion engine of the aspiration type. In its broader aspects, however, my invention is capable of being used with other types of engines, including injection engines. Accordingly, the term "gas-electric drive" as used

5 in the descriptive matter of the specification and the claims is to be construed broadly and as covering the use of my invention with any type of engine with which it is capable of being used, except in such instances as this

10 term is necessarily used in its restricted sense.

Having described my invention, I claim as follows:—

15 1. In a gas-electric drive system, the combination of an internal combustion engine, a governor therefor, a manually controllable throttle for the engine, a generator driven by the engine, a generator governor operated by the engine to control the generator field circuit, a governor spring for said generator governor, and a hand lever controlling the tension of said spring.

20 2. In a gas-electric drive system, the combination of an internal combustion engine, an engine governor therefor, a manually controllable throttle for the engine, a generator driven by the engine, a generator governor driven by the engine to control the generator field, a regulating spring for the generator 25 governor, setting mechanism for setting the tension of said spring, and propulsion motors receiving current from said generator.

30 3. In a gas-electric power unit, the combination of an internal combustion engine, a generator driven thereby, a field circuit for said generator, a resistance for said field circuit, a tickler circuit for the generator, a governor driven by the engine and connected to control said resistance, and manually operable means for modifying the action of said 35 governor and for controlling the opening and closure of said tickler circuit.

40 4. In a gas-electric power unit, an internal combustion engine, a constant speed governor for said engine, a separate manual throttle control for the engine permitting reduction of the engine speed below governed speed, a generator driven by the engine, a separate governor driven by the engine and connected to control the generator characteristics to thus regulate the load on the engine, a spring for said generator governor, and a manually controlled lever for regulating the tension of said spring.

45 5. In combination in a gas-electric drive, an engine with a throttle, an electric generator driven by the engine, a variable generator field resistance, an electric motor driven by the generator, a governor driven by the engine, and means actuated by the governor and acting to vary the generator field resistance from maximum to minimum and vice versa for a predetermined narrow range in engine speed and inversely as the engine 50 speed, whereby the generator excitation is

varied thus varying the load on the engine and maintaining the engine speed within certain predetermined limits independently of throttle position of resistance of the motor circuit.

70 6. In combination in a gas-electric drive, an engine, a shaft driven by the engine, an engine governor on said shaft, an electric generator driven by the engine and having a variable field resistance, a generator governor on the shaft, and means actuated by the generator governor for varying the field resistance of the generator inversely as the engine speed.

75 7. In combination in a gas-electric drive, an engine, a shaft driven by the engine, an engine governor on said shaft, an electric generator driven by the engine and having a variable field resistance, a generator governor on the shaft, means actuated by the generator governor for varying the field resistance of the generator inversely as the engine speed, a throttle for the engine, and means for operating said throttle independently of 80 the governors.

8. In combination in an electric drive, an engine, means for varying the supply of fuel to the engine, an electric generator driven by the engine, a variable generator field resistance, an electric motor driven by the generator, a governor driven by the engine, and means actuated by the governor and acting to vary the generator field resistance from maximum to minimum for a predetermined narrow range in engine speed and inversely as the engine speed, whereby the generator excitation is varied thus varying the load on the engine and maintaining the engine speed within certain predetermined limits under wide variation of fuel supply to the engine.

90 In witness whereof, I hereunto subscribe my name this 15th day of July, 1926.
